UNITED STATES PATENT OFFICE.

ALEXANDER M. SCHNEIDER, OF NEW YORK, N. Y.

ADJUSTABLE GARMENT.

1,071,353.

Specification of Letters Patent. Patented Aug. 26, 1913.

Application filed September 19, 1912. Serial No. 721,222.

To all whom it may concern:

Be it known that I, ALEXANDER M. SCHNEIDER, a citizen of the United States, residing at New York city, county and State of New York, have invented a new and Improved Adjustable Garment, of which the following is a specification.

This invention relates to a garment of the class which is adjustable at the waist such as described in Patent No. 1,009,262 issued to me November 21st, 1911. In that patent a permanently doubled portion of the waist band carries one fastening member that cooperates with a second fastening member carried by a flap which is secured to the waist band and is adapted to be passed through a selected aperture thereof. By this construction which is well adapted for garments made of silk, muslin or other thin material, four thicknesses of fabric are thus presented at the point of engagement with the fastening members. With garments made of heavier material, such as knitted or other underwear, this quadrupling of the fabric at said point of engagement is however objectionable for the reason that it forms an undesirable bulging of the garment and renders the fasteners liable to become accidentally opened. The present invention is designed to overcome this objection, the construction being such that at the point of engagement with the fasteners, but three layers of material are encountered so that the aggregate thickness of the garment is materially diminished, while an accidental opening of the fasteners is prevented.

In the accompanying drawing: Figure 1 is a perspective view of the upper part of a garment embodying my invention; Fig. 2 a top view thereof with the fastener closed; Fig. 3 a perspective view of a modification, and Fig. 4 an inner face view thereof.

Referring more particularly to Figs. 1 and 2 which show the invention applied to a pair of drawers, the numeral 10 represents the waist band provided with shortening means on its right and left sides, such shortening means being identical in construction. The shortening means comprise a row of button holes or slits 11 formed along portion of the waistband. Directly back of said row, there is secured to the outer side of the waistband by an upright seam 12, a relatively short tab 13, carrying a button or similar male fastening member 14, which is

normally directly opposite the rearmost button hole 11. To the inner side of the waistband, there is secured by an upright seam 15, a relatively long tab 16 having a button hole or similar female fastening member 17, which is adapted to coöperate with button 14. Seam 15 is set back from seam 12, a distance equal to the difference in length between tabs 16, 13, so that the front or free ends of the tabs will be alined with each other and the button hole 17 will be placed directly opposite the button 14.

When the garment is to assume its maximum width, button 14 is passed through the rearmost button hole 11 and also through the button hole 17 of tab 16. If the waist measure of the garment is to be shortened, the button-holed portion of the waistband is doubled up to the extent desired and the doubled section is tucked in underneath the longer or innermost tab 16, after which the button 14 is passed through that particular button hole 11 which has become alined therewith and also through the button hole 17 of tab 16. In this way the waist band becomes fixed in its shortened condition and will retain its new form even under severe strain. It will be seen that by the construction described, the doubled portion of the waistband is tucked in underneath the rear portion of the longer tab 16, while between the front portion of said tab and the shorter tab 13 but a single thickness of waistband is interposed. In this way, there are encountered at the point of engagement with the fasteners but three layers of fabric, so that the thickness of the garment is not unduly increased and that any accidental opening of the fasteners is effectively obviated.

In Figs. 3 and 4, the invention is shown to be applied to a skirt. Here the two adjustable sections of the waistband 18 are arranged in close proximity to each other at the back of the skirt. The two outer and shorter tabs 19 are secured by the upright seams 20 to opposite ends of the two rows of apertures 21. The two inner and longer tabs 22 are made integral with each other, comprising a single piece of fabric which is stitched to the garment by an upright central seam 23 and extends some distance below the waistband to here constitute a reinforcement. The fastening means carried by the tabs 22, 19 are shown to be made in the form of conventional coöoperating snap but-

tons 24 and sockets 25, while the openings 21 of the waistband are of round form to accommodate the same.

I claim:

- 5 An adjustable garment provided with a waistband having a row of apertures, a pair of tabs of different lengths secured to opposite sides of said waistband in proximity to said row, the longer tab being secured to the waistband back of the shorter tab at a distance, equaling the difference in the length between the tabs, a fastening member on one of said tabs which is adapted to be projected through one of said apertures,
- 10

and a coöperating fastening member on the 15 other tab, the apertured waistband section being adapted to be doubled between the long tab and the waistband of single thickness that extends between the points of attachment of the long and short tabs to said 20 waistband, while the garment is of but triple thickness at the points of engagement with the fastening members.

ALEXANDER M. SCHNEIDER.
